Patented Jan. 8, 1918.

UNITED STATES PATENT OFFICE.

WILLIAM B. HOLLINGSHEAD, OF CHICAGO, ILLINOIS.

DUPLEX ENVELOP.

1,252,804.

Specification of Letters Patent.

Patented Jan. 8, 1918.

Application filed May 11, 1917. Serial No. 167,874.

To all whom it may concern:

Be it known that I, WILLIAM B. HOLLINGSHEAD, a citizen of the United States, and resident of Chicago, in the county of Cook and State of Illinois, have invented certain new and useful Improvements in Duplex Envelops, of which the following is a specification, reference being had therein to the accompanying drawing.

10 My present invention refers to a double compartment envelop or package intended to contain contribution money for different purposes, and especially adapted for use by missionary and benevolent societies and 15 organizations where it is desired to apportion the moneys collected to various objects.

The object of the invention is to provide a simple, economical, and efficient device of the class described, and which will furnish 20 two or more pouches or inclosures for the reception of contributions, which inclosures are effectively bound and closed so that their contents may not be dissipated, and which inclosures further are easily separable from 25 each other so that a perfectly sealed compartment, inclosure, or envelop may be handed to each of the objects for which the offerings are being made. The invention, therefore, may be said to consist essentially 30 in the construction, arrangement and combination of parts, substantially as will be hereinafter described and then more particularly pointed out in the annexed clauses of claim.

35 In the accompanying drawing illustrating my invention:

Figure 1 is a rectangular blank which is to be folded on predetermined lines to form my improved duplex envelop;

40 Fig. 2 is a view of the same when partially folded;

Fig. 3 is a further side view of the same after another fold has been made;

Fig. 4 is a side view of the completed 45 envelop with all folds and sealings made thereon excepting the final sealing of the triangular binder which is shown in its idle position;

Fig. 5 is another side view of the completed 50 envelop sealed and bound by the additional sealing of the triangular binder;

Fig. 6 is a side view of the envelop when folded in the same manner as it is shown in

Fig. 2, but viewed from the other side so as to indicate the gummed edges of the flaps of 55 the pouches;

Fig. 7 is a perspective view of one of the sealed and bound edges or compartments of the envelop when severed from the other;

Fig. 8 is a cross-section on the line 8, 8 of 60 Fig. 5;

Fig. 9 is a cross-section on the line 9, 9 of Fig. 5.

Similar characters of reference designate corresponding parts throughout the different 65 figures of the drawing.

The blank out of which my present improved duplex envelop is made, is preferably rectangular in form, as shown in plan view in Fig. 1, being of greater or less size, and 70 with its linear dimensions variable within wide limits, provided only it is susceptible of being folded according to the general plan of my invention so as to furnish a pair of envelopes, pouches, inclosures, or compartments, having a general triangular shape and adapted to be left as a single duplex 75 unit or severed into two independent single units accordingly as the accounting methods for the collections may render necessary. 80 This main blank is creased first on the transverse parallel lines 3, 3 which are at a short distance from the ends 7, so as to provide the narrow flaps or sealing covers 8 which are preferably gummed at 12. 85

The next fold will be on diagonal lines 5, 5 running from corresponding ends of the lines 3, 3 to the opposite end of the central transverse line 2, which is the median line of the envelop and on which the next fold is 90 made for the purpose of preliminarily forming the two pouches. Referring for example to Figs. 2 and 3, it will be seen how the folds are made on these diagonal lines 5, 5 to cause the triangular sections 9, 9 to lie flat upon the triangular sections 10, 10 with the flaps 8, 8 creased but not yet folded over, as the folding and sealing of the flaps 8, 8 will take place only after the pouches have been filled in use. When the triangular sections 9, 9 100 lie superposed upon the triangular sections 10, 10, as viewed from one side in Fig. 2 and from the other side in Fig. 6, it will be seen that the edges 6 of the triangular sections 9, 9, which are gummed at 13, will lie upon the 105 triangular sections 10, 10 closely contiguous

to the median line 2 of the envelop and the adhesive at 13 may be caused to securely fasten the edges 6, 6 to the sections 10 near the line 2 whereby two receptacles of triangular shape will be formed, which receptacles can be placed so that one will lie on or opposite to the other by merely bending the blank along the median line 2 in the shape indicated in Fig. 3 where I present the duplex pouches with their flaps 8 raised over the mouths of these pouches in readiness to receive the insertion of the collection moneys therein either in one or both of the pouches, as desired. After either pouch is filled the flap 8 can be sealed down over the section 10, thereby covering the edge 1 and the mouth, and being adhesively attached to the section 10, the pouch, either one or both of them as the case may be, will be effectively closed.

Thus we have the two pouches which are entirely independent of each other, except that they are attached together in a single unitary structure. The ends of the flaps 8 are provided with triangular binders 4 caused by bending over the ends of these flaps 8 on the inclined lines 14, and as each of the triangular binders 4 contains a portion of the adhesive material 12 applied to edge 7 of flap 8, it will be seen that each binder 4 is prepared to be sealed and turned over the adjoining portion of the envelop. When the triangular binder is not used, or before it is used, the envelop will, after the flap 8 has been sealed down to cover the mouth of the pouch, appear as indicated in Fig. 4, but when the binder 4 is sealed in place, it will be turned over the edge, as indicated in Fig. 5, and this binder may obviously be used for the purpose of completing the sealing of each single pouch or for the purpose of sealing together the two pouches, in which case one of the binders will overlap and be sealed to the other pouch, that is to say, these triangular binders 4 may simply complete the sealing of individual pouches by being turned over and sealed to its own pouch, or one of them may be sealed to its own pouch and the other turned over the edge of the adjoining pouch and sealed thereto, in which case we will have two pouches or compartments completely inclosed and effectively sealed in one substantial structure which can be handled in any desired manner without any commingling of their contents and without any dissevering under ordinary uses of the two pouches. When, however, it is desired to separate these pouches in order that they may go to different treasurers or societies, then by the aid of a knife or paper cutter the two inclosures or compartments may be readily dissevered from each other by running the knife between the two pouches and severing them along the split back which is the median line

2, which is immediately between the two gummed edges 13 and also, if one of the triangular binders has been sealed to unite together the two pouches, severing likewise the said triangular binder so that the two triangular inclosures are separated from each other and made entirely independent. One of these independent inclosures after being severed from the other is shown in perspective view in Fig. 7.

I lay particular stress and emphasis therefore upon the ability of this device to be cut along its split back into two separate devices, and also I wish to emphasize the triangular binding corner which enables the front edges of the triangular pouches to be connected together securely and strongly after both pouches have been filled and sealed. This makes the envelop much more compact than if the device were allowed to retain the general form and position shown in Figs. 2 or 5 with their flaps sealed but without having the outer portions of the triangular pouches connected, for when they are connected the device is simpler and better in every way. Further with the split back it is possible for one side of the envelop to be used unsealed and the other sealed, which serves as a time saver to the treasurer and a constant reminder to the contributor. With two pouches arranged and related in the manner that I have described, it will be found impossible for coins to slip from one side to the other through any defective gumming when the device is finally sealed or bound. With the double sealing device, it is evident that the envelop may be used for either side or for both sides even when one side contains no coin. When the envelop is sealed and bound, there is no disclosure of the contents in any way.

It is further to be noted that the face of one or both of the triangular inclosures, as also the flaps, and in fact all parts of the envelop may be covered with suitable printed blanks or other designations to differentiate the compartments from each other and to represent by dates and numbers the times for making the collection, the number of the contributor, and other necessary data for the proper accounting of the contributions and with the lists of the objects for which the contributions are supplied, scripture texts, and other matter which may be useful or desirable with envelops of this character, and although I have not found it necessary to represent these in the drawings because of their wide variety, I intend to reserve the liberty of furnishing the envelops with all such printed matter as may be found desirable.

Many changes in the precise details and relative sizes and shapes of the several parts of the blank and the way in which they are

combined and related for the purpose of performing the functions as specified, may be made in the same and I reserve the liberty of modifying and adjusting these features

5 within wide limits.

Having thus described my invention, what I claim as new and desire to secure by Letters Patent, is:—

1. In a duplex envelop, a blank having its 10 ends folded to provide flaps having at their ends binding corners, and being also folded on lines running from the top of the flaps to the middle point of the bottom of the blank, the whole being sealed to furnish two separable 15 separate inclosures.

2. In a duplex envelop, a rectangular blank having its ends folded to provide flaps and being also folded on diagonal lines running from the flaps to a middle line on which 20 it is likewise folded, the whole being sealed so as to provide a duplex unit which furnishes two separate inclosures that are easily separable from each other.

3. In a duplex envelop, a rectangular blank 25 having its opposite ends folded to provide adhesive flaps, the ends of which have foldable corners to provide binding flaps and the blank being also folded on a central line and on diagonal lines running from one end 30 of the central line to the flap creases, the

whole being folded to provide two separate pouches or compartments that can subsist in a unitary structure or be separable into two distinct individual envelops.

4. In a device of the class described, a 35 rectangular blank which is foldable on a central line into two sections, each one of which is foldable into a triangular pouch, each pouch having a flap and a triangular binder, and the whole device being capable of being 40 severed into two individual compartments or kept as a single unitary structure.

5. In an envelop device of the character described, a blank foldable on the central line to provide two sections, each of which is 45 foldable into the form of a triangular pouch, said pouches being connected alongside said central line which is severable to divide the device into two independent pouches.

6. In a duplex envelop, a pair of triangular compartments formed integral with each other and connected at a central severable line, said compartments being provided with individual sealing flaps having each a folded binding corner whereby the edges of the compartments may be sealed together at a point 50 opposite to the severable connection.

In testimony whereof I hereunto affix my signature.

WILLIAM B. HOLLINGSHEAD.
